UNITED STATES PATENT OFFICE.

VANDIVER J. VAN HORN, OF CHICAGO, ILLINOIS, ASSIGNOR TO UNION SPECIAL MACHINE COMPANY, OF CHICAGO, ILLINOIS, A CORPORATION OF ILLINOIS.

THREAD-CUTTER FOR SEWING-MACHINES.

1,145,636.

Specification of Letters Patent.

Patented July 6, 1915.

Application filed April 14, 1908. Serial No. 427,029.

To all whom it may concern:

Be it known that I, VANDIVER J. VAN HORN, a citizen of the United States, residing at Chicago, in the county of Cook, State 5 of Illinois, have invented certain new and useful Improvements in Thread-Cutters for Sewing-Machines, of which the following is a description, reference being had to the accompanying drawing, and to the letters and 10 figures of reference marked thereon.

My invention relates to new and useful improvements in thread cutters for sewing machines, and while I have herein shown my thread cutter as applied to a zigzag stitching machine, it is evident that said thread cutter may be used in connection with various types of sewing machines.

An object of my invention is to provide a thread cutter for a sewing machine which is 20 so arranged and operated that the thread may be cut at a point above the material, and drawn through to the underside of the material, whereby the stitches are locked so that they cannot unravel.

25 A further object of my invention is to provide a combined thread cutter and tension device, whereby the tension on the thread may be released and then the thread cut.

30 A further object of my invention is to provide means for drawing the thread through the eye of the needle to provide a quantity of thread between the eye of the needle and the material, and then to cut the 35 thread close to the surface of the material.

35 A further object of my invention is to provide a thread cutter with means for operating the same, and means for preventing its operation except when the needle is well 40 above the material.

45 A still further object of my invention is to provide a thread cutter with means for operating the same, including a cutter reciprocating across the path of the needle and also providing means for preventing the operation of the machine, when the cutter is in the path of the needle.

50 A still further object of my invention is to provide a thread cutter operating across the path of the needle, and means for positively withdrawing the thread cutter by the needle

operating means, so that said needle cannot be accidentally caused to strike the cutter.

Further objects of my invention will in part be obvious, and will in part be more 55 fully hereinafter described.

In the drawings which show by way of illustration, one embodiment of my invention: Figure 1 is a side view of a sewing machine with my thread cutter applied 60 thereto. Fig. 2 is a detail perspective view of the thread cutter and tension release and the operating mechanism therefor. Fig. 3 is a perspective view of the thread cutter with the parts positioned for cutting the 65 thread. Fig. 4 is a sectional detail view of the pull off device, operated in connection with the cutter. Fig. 5 is a sectional view showing the position of the needle thread at the time it is cut. Fig. 6 is a detail view 70 showing the operating parts for the cutter when the cutter is across the path of the needle. Fig. 7 is a detail view showing the presser foot in raised position. Fig. 8 is a similar view from the other side. 75

In the present embodiment of my invention, I have shown a sewing machine which comprises a work support 1, an overhanging arm 2, a needle lever 3, which is pivoted at 4 to the overhanging arm, and is reciprocated by a link 5 from the main shaft 6, by the usual belt wheel 7. Said lever 3 is connected by means of a link 8 to the needle bar 9, which carries a needle 10 at the lower end thereof. Said needle bar 9 is mounted to 80 reciprocate in a needle gate 11 pivoted in the usual manner, so that said needle bar may be vibrated laterally for the purpose of forming zigzag stitches. Said needle gate 11 is connected to a rock shaft 12 which is 85 vibrated by a pivot fork 13. These parts are of the usual construction and will not need further description in this connection. It should be clearly understood, however, that while I have shown my thread cutter 90 as attached to a zigzag stitching machine, said thread cutter may be used in connection with any other type of sewing machine.

Cooperating with the needle 10 beneath the work support 1 is a looper 14 which is 100 oscillated by means of a link 15 connected to an extension formed on the needle lever 3.

The needle thread is led from the supply between tension disks 16 and 17 mounted on a stud 18 and a spring 19 presses said tension disks 16 and 17 together, this creating the desired tension on the needle thread. The 5 needle thread is led from the tension disks 16 and 17 to a thread eye 20 on the needle lever and thence to a controller 21 which is controlled by the presser foot in the usual manner in this type of machine. The thread 10 is then passed through an eyelet 22 carried by the needle lever from which it is led to an eyelet 23 at the upper end of the needle bar. The presser foot 24 of the machine is 15 carried by a presser bar 25 in the usual manner. Said presser foot 24, is provided with the usual needle slot 26.

My improved thread cutter consists of a cutting blade 27 which is mounted on the 20 upper side of the presser foot in the present illustrated embodiment of my invention, and is adapted to be reciprocated across the needle slot 26. As a means for guiding the cutter 27, I have provided my presser foot 25 with a guide plate shield 28 which is secured to the upper surface of the presser foot by means of a screw 29 and a pin 30 which passes through an opening in the forward end of the plate 28. Said plate 28, is provided 30 with a slot which registers with the needle slot 26. At the forward end said plate 28 is bent around underneath the forward end of the upturned portion of the presser foot 24. The upper surface of the 35 presser foot is recessed to form a guideway for the cutting blade 27 and the plate 28 closes the upper side of said recess.

The cutting blade 27 is provided with a rearwardly extending shank 31, which is 40 pivotally connected to the forked end of a rod 32 sliding in a sleeve 33 which is pivoted at 34 to a bracket 35 carried by the head of the machine. As the sleeve 33 is oscillated about its pivotal support 34, the cutter blade 45 27 will slide back and forth in the recess in the upper surface of the presser foot. As a means for oscillating the sleeve 33 about its pivotal support, I have provided said sleeve with a forwardly projecting arm 36 which 50 engages a suitable opening 37 in the lower end of a sliding bar 38. Said sliding bar 38 is mounted in a guide-way formed in the overhanging arm of the machine. As said bar 38 slides up and down in its guide-way, the cutter will therefore be reciprocated 55 across the path of the needle. The loose connection between the sliding bar 38 and the arm 36 of the cutter operating sleeve allows the sliding bar 38 to move in a right line.

60 In order to pull through the eye of the needle a certain amount of thread so that when the thread is cut, a sufficient length of thread is left through the eye of the needle that the stitching may properly commence, I 65 have provided the following means: A

thread loop 39 is arranged so as to normally encircle the path of the needle and therefore the thread running from the needle eye to the stitching point, will pass through said thread loop.

70 The thread loop as shown in the present embodiment of my invention is formed of wire which is triangular in shape, and which is pivoted at 40 to a sliding bar 41. A

75 spring 42 operates upon said thread loop 39 and normally presses the same toward the rear of the machine. A stop shoulder 43

carried by said thread loop engages a projection 44 on the sliding bar 41, and limits the rearward movement of said thread loop. 80

The sliding bar 41 is provided with a shank 45 which extends up into a supporting sleeve 46. The sleeve 46 is formed with a contracted opening at its lower end, which 85 serves as a stop and the shank 45 is provided with an enlarged head 47, which engages the stop and thus limits the downward movement of the shank 45 and the bar 41, relative to the sleeve 46. A spring 48 located within the sleeve 46, engages the enlarged head 47 90

at one end, and a closing screw 49 at the other end, and normally forces the bar 41 and the thread loop in a downward direction, relative to the sleeve 46. Said sleeve 46 is also provided with a downwardly extending 95

lip 50 which serves as a guide for the bar 41, and also serves as a means for preventing oscillations of said bar 41, and the thread loop 39. The sleeve 46 is carried by a sliding bar 51 which is slotted and provided with a guiding screw or screws 52 so 100

that said bar may slide vertically carrying with it the sleeve 46 and the thread loop 39. The sliding bar 51 is connected by a link 53 to a lever 54 pivoted at 55 to the overhanging arm. Said lever 54 is also provided with a downwardly extending curved arm 56. As a means for oscillating the arm 54, I 105 have provided a rock shaft 57 which is mounted in a bearing block 58, supported by 110 the overhanging arm. Said rock shaft 57 is provided with an arm 59 which extends downwardly and normally rests in contact with the downwardly extending arm 56 of the lever 54. The rock shaft 57 is also provided with an arm 60 which may be suitably connected with an operating treadle or knee shift. It will be obvious therefore, 115 that as the rock shaft 57 is oscillated, the arm 59 will bear against the arm 56 and thus oscillate the arm 54 which in turn will reciprocate the bar 51 and the sleeve 46, carried thereby and thus give to the thread loop 39 a reciprocation. The spring 61 engages the lever 54 at 62, and a suitable stud 63 on the 120 arm of the machine, and normally tends to hold the forward end of the lever 54 in its lowered position. The sleeve 46 is connected to a block 65 which is connected by means of screws to the lower end of the sliding bar 125

130

51. Said block 65 at its upper end is provided with a contact shoulder 66, projecting into the slotted portion of the bar 51. The sliding bar 38 which operates the cutter blade is located directly in rear of the sliding bar 51 and is provided with a shoulder 67 near its lower end, which is located in the path of movement of the lower end of the sliding bar 51. The upper end of the sliding bar 38 is provided with a forwardly projecting lug 68 which extends into the slot in the sliding bar 51, and is located in the path of the contact shoulder 66. The shoulder 67 and the lug 68 are spaced so that the sliding bar 51 has considerable range of movement before the sliding bar 38 will be operated.

The operation of my device is as follows:—The spring 61 normally holds the lever 54 with its forward end lowered and with the sliding bar 51 thrown down so as to contact with the shoulder 67 throwing down also the sliding bar 38. In this position of the parts, the thread loop as shown in Fig. 2 is in its forward position encircling the path of the needle and the needle thread extends from the eye of the needle through said thread loop to the material. The arm 38 of the sleeve 33, is in its lower position and the cutter blade therefor, retracted. The operator now oscillates the rock shaft 57, which in turn oscillates the lever 54, moving up the slide 51. In the first upward movement of the sliding bar 51 there will be no movement imparted to the cutter blade. As the bar 41 carrying the thread loop moves upward, the spring 42 will cause the thread loop which was resting on the presser foot, to move toward the rear of the machine, and cross the path of the needle carrying with it the needle thread. A further movement of the sliding bar 51 carries the thread loop up in rear of the needle to a position considerably above the eye of the needle, which will pull thread through the eye of the needle. Just before the sliding bar 51 reaches its extreme upper position, the contact shoulder 66 strikes the lug 68 and operates the sliding bar 38, which in turn forces the cutter blade across the thread slot in the presser foot, and cuts the needle thread close to the material. When the rock shaft 57 is released by the operator, the spring 61 throws down the forward end of the lever 54 and the sliding bar 51 is lowered, carrying the thread loop 59 downward to the position shown in Fig. 2. The sliding bar 51 in its downward movement strikes the shoulder 67 and forcing down the arm 38 positively withdraws the cutter blade.

As a means for releasing the tension on the needle thread, so that the needle thread may readily be drawn through the eye of the needle, I have provided the rock shaft 57 with a pivoted tension releasing arm 69,

which is pivoted at 70 to the arm 59. The upper end of the tension releasing arm extends to a position adjacent the tension disks 16, 17, so that when the arm 69 is oscillated, the upper end thereof is crowded between the tension disk separating the same, so as to relieve the tension on the needle thread. The lower end of the arm 69 is provided with a stop screw 71, engaging the lower end of the arm 59. Said arm 69 at its lower end is provided with a laterally projecting portion 72 which carries an adjustable screw 73 located so as to contact with the standard of the machine. As the rock shaft 57 is oscillated, the pivotal point of the arm 69 is carried forward and the stop screw 73 is brought into contact with the standard of the machine, and this throws the upper end of the arm 69 forward between the tension disks. A spring 74 carried by the rock shaft 57, engages the arm 69 below the pivotal point 70, and normally throws the upper end of said arm away from the tension disks. The screw 71 limits the outward movement of the upper end of the arm 69. I have provided the needle lever 3, with a stop block 75 which is located at a point adjacent the lower end of the arm 56. This stop block 75 partakes of the movement of the needle lever 3. When the needle is raised above the material, the stop block 75 is carried down so as to be out of the path of the lower end of the arm 56, as shown in Figs. 1 and 2. The operator may now oscillate the rock shaft 57 and operate the thread cutter. If, however, the needle is down so that the same will be struck by the cutter blade, if the thread cutter were operated, the stop block 75 is carried up into the path of the arm 56, so that the thread cutter can not be operated. If the needle is in raised position and the cutter blade operated and for some reason the machine should be started, the stop block 75 will immediately strike the arm 56 and throw the lever 54 so as to positively throw the cutter blade from across the path of the needle. It will be seen therefore, that I have provided mechanism whereby the thread cutter can only be operated when the needle is at its extreme upper position, and furthermore, if the machine should be accidentally started with the cutter blade across the needle slot, the machine itself, will automatically operate to withdraw the cutter.

When the cutter blade is withdrawn from across the needle slot, and the thread loop 39 is in its lowered position, so that the machine is in position for stitching, I may readily raise the presser foot for the insertion of the work if desired. The rod 32 loosely engages the sleeve 33 so that the presser foot may be raised as the bar 32 readily slides up into said sleeve. The shank 45 for supporting the thread loop 39,

may also readily slide up into the sleeve 46 compressing the spring 48 so that it will readily be seen that the presser foot may at any time be raised or lowered without disturbing the position of the thread cutter or the thread loop or the operating parts therefor.

When the needle is at the upper part of its stroke, the looper is at the forward end 10 of its stroke and the needle thread extends down through the needle puncture around the looper and to the previous interlocking of the needle and the looper threads. When the thread cutting blade is therefore operated 15 to cut the needle thread, the needle thread as above noted, extends down around the looper. If therefore, the material is withdrawn from the machine after the needle thread is cut, the looper will operate to 20 pull the end of the needle thread down through the material to the lower side thereof, which will serve to lock the threads and prevent unraveling. It will therefore, be seen that my invention contemplates not 25 only the cutting of the needle thread, but the drawing of the same to the under side of the material, whereby the desired locking of the threads is secured.

It will be noted that the tension releasing 30 arm 69 moves almost entirely through the tension device as shown in Fig. 6. The result of this movement is, that the thread will be first released so as to be readily pulled through the tension by the thread loop and 35 after the arm reaches the opposite side of the tension disks, they will tilt, and close on the thread on the right hand side as viewed in Fig. 6. This gripping of the thread will cause the thread loop on the last part of its 40 movement to pull the thread up tight. It will also be noted that the spring 61 operates to automatically return the parts to normal position, as soon as the arm 60 is released.

It will be obvious that my thread cutter 45 may be operated by mechanical means controlled manually and that many changes may be made in the details of construction or arrangement of parts without departing from the spirit of my invention.

Having thus particularly described my invention, what I claim as new and desire 50 to secure by Letters Patent is:—

1. A sewing machine including in combination, a needle, a thread cutter, manually-operated means for operating said thread cutter and means for preventing the operation of said manually operated means, except when the needle is above the material and out of the path of said thread cutter.

2. A sewing machine including in combination, a needle, a thread cutting blade, manually-operated means for reciprocating the same across the path of the needle, and means for preventing the operation of said blade reciprocating means except when the

needle is out of the path of said cutting blade.

3. A sewing machine including in combination, a presser foot, means for lifting the presser foot, a needle, means for engaging the needle thread between the eye of the needle and the material for pulling thread through the eye of the needle, means above the material for cutting the needle thread at a point adjacent the material, and means 75 for preventing the operation of said cutting means except when the needle is raised above the material.

4. A sewing machine including in combination, a presser foot, means for raising the 80 presser foot, a needle, a thread cutting blade moving across the path of the needle above the material, means operating to pull thread through the eye of the needle and subsequently cut the thread at a point adjacent 85 the material, and means for preventing the operation of the thread-cutting blade except when the needle is above said blade.

5. A sewing machine including in combination, a needle, a thread-cutting blade moving across the path of the needle above the material, means for pulling thread through the eye of the needle and for subsequently 90 operating said cutting blade to cut the thread at a point adjacent the material, means for preventing the operation of the cutting blade except when the needle is above said blade, and means for pulling the 95 end of the cut thread through the material.

6. A sewing machine including in combination, a needle, a presser foot mechanism and means for lifting the same, a tension device, and manually operated mechanism for first releasing the tension on the needle thread, then pulling thread through the eye 100 of the needle, and then cutting the thread at a point above and adjacent the material before the presser foot is lifted.

7. A sewing machine including in combination, a needle, a tension device, and manually operated mechanism for first releasing the tension on the needle thread, then pulling thread through the eye of the needle, and then cutting the thread at a 110 point above and adjacent the material, and means for pulling the end of the cut thread through the material.

8. The combination of a needle, a thread cutter, and means for pulling thread through the eye of the needle prior to the cutting of the thread, including a thread loop surrounding the path of the needle.

9. The combination of a needle, a thread cutter, and means for pulling thread through the eye of the needle prior to the cutting of the thread, including a slide, a pivoted thread loop carried thereby, and surrounding the thread leading from the eye 125 of the needle to the material.

10. The combination of a needle, a thread 130

cutter, and means for pulling thread through the eye of the needle prior to the cutting of the thread, including a slide, a sleeve carried thereby, a bar having a sliding connection with said sleeve, and a thread loop carried by said bar and adapted to engage the thread between the eye of the needle and the material.

11. The combination of a needle, a thread cutter, and means for pulling thread through the eye of the needle prior to the cutting of the thread, including a sliding bar, a sleeve carried thereby, a bar having a shank sliding in said sleeve, a guide plate for preventing oscillation of said bar, and means for engaging the needle thread between the eye of the needle and the material supported by said bar.

12. The combination of a needle, a thread cutter, and means for pulling thread through the eye of the needle prior to the cutting of the thread including a sliding bar, a sleeve carried thereby, a bar having a shank sliding in said sleeve, a guide plate for preventing oscillation of said bar, a thread loop pivoted to said bar, a spring operating to turn said thread loop about its pivot and stops for limiting the movement of said thread loop.

13. A sewing machine including in combination, a needle, a presser foot, a thread cutting blade guided by said presser foot, manually-operated means for reciprocating said thread cutting blade across the path of the needle, and means for preventing the operation of said blade except when said needle is at the upper end of its stroke.

14. A sewing machine including in combination, a main shaft, a needle, means actuated by said main shaft for reciprocating said needle, a thread cutting device, means for moving said device across the path of the needle to cut the needle thread, and means operated by the needle actuating means for positively withdrawing the thread cutting device from the path of the needle on the first part of the downward movement of the needle and before the needle reaches the cutting device.

15. A sewing machine including in combination, a needle, means for operating the same, a thread cutter, manually controlled means for operating the cutter and means operated by said needle operating means for preventing the operation of said manual means, except when the needle is at the upper end of its stroke.

16. The combination of a presser foot, a thread cutting blade supported by said presser foot, means carried by the head of the machine for reciprocating said thread cutting blade, said means including a sliding connection, whereby the presser foot may be lifted, when desired without operating the cutting blade.

17. The combination of a presser foot, a cutter blade supported by said presser foot, means for operating said cutter blade including a sleeve pivoted to the head of the machine and having a sliding connection with said cutter blade, whereby said presser foot may be lifted when desired without operating the cutting blade.

18. The combination of a thread cutter and means for operating the same, including a vertically arranged sleeve, a horizontal pivotal support for attaching said sleeve to the head of the machine, means for oscillating the sleeve, and means having a sliding engagement with the sleeve and connected to the thread cutter, for operating the same when the sleeve is oscillated.

19. The combination of a thread cutter including a cutting blade and means for operating said blade, including a vertically arranged sleeve pivoted to the head of the machine, a bar sliding in said sleeve and having a pivotal connection with the cutting blade, an arm extending laterally from said sleeve, and means engaging said arm for oscillating the sleeve to operate the cutter.

20. The combination of a presser foot having a recess in its upper face, a cutter blade mounted therein, means for reciprocating said cutter blade, and a plate secured to the upper face of said presser foot, and holding said cutter blade in its guiding recess.

21. A sewing machine including in combination a work support, a needle, a looper coöperating with said needle beneath the work support, a thread cutter operating to cut the needle thread above the material, means for operating the thread cutter, and means for preventing the operation of the thread cutter, except when the needle is raised and the looper is forward in the needle thread loop.

22. The combination of a needle, a tension device for the needle thread, means for pulling thread through the eye of the needle, said means including a rock shaft, an arm pivoted to said rock shaft, and operating to release the tension, an adjustable screw carried by said arm, and a stop coöperating with said adjustable screw.

23. The combination of a tension device, with means for releasing the tension, including a rock shaft, an arm carried thereby, and operating to release the tension, a spring for throwing said arm in one direction, a stop screw for limiting the movement of said arm, and an adjustable screw and co-operating stop, for causing the movement of said arm, when said rock shaft is oscillated.

24. The combination of a thread cutter including a cutting blade, a slide for operating said cutting blade, said slide being

3
provided with spaced lugs, a second slide having contacting shoulders for engaging said lugs, said lugs being spaced a greater distance than the contacting shoulders, 5 whereby the second slide, may have a limited movement before operating said first named slide, and a thread pull off, operated by said second named slide.

25. The combination of a needle, and 10 means for pulling thread through the eye of the needle, including a reciprocating member, a thread loop carried thereby, and adapted to engage the needle thread, between the eye of the needle and the material, 15 a spring for oscillating said thread loop, and stops for limiting the movement thereof.

26. The combination of a needle, a thread 20 cutter and means for pulling thread through the eye of the needle prior to the cutting of

the thread, including a slide, a pivoted thread loop carried thereby and surrounding the thread leading from the eye of the needle to the material, said thread loop being spring pressed.

25

27. A sewing machine including in combination, stitch forming mechanism having a needle, a thread cutter, having a cutting blade reciprocating across the path of the needle means for drawing thread through 30 the eye of the needle and means for preventing the operation of the stitch forming mechanism, while said cutter blade is in the path of the needle.

In testimony whereof I affix my signature, in presence of two witnesses.
